RECORD FILING MEANS

Herbert V. Emblen and Melvin D. Baker,
San Diego, Calif.

Application October 4, 1943, Serial No. 504,814

2 Claims. (Cl. 129—16)

Our invention relates to filing means for records, such as loose-leaf accounting ledges leaves with readily visible index, or like subject matter, and the objects of our invention are:

First, to provide a record filing means of this class in which either single or double leaves are shiftably positioned so that they may be read from either side of each leaf and written on either side of each leaf;

Second, to provide a novel file folder in which the separate record leaves may be easily removed and replaced without removing other leaves of the same folder;

Third, to provide a combined folder and leaf arrangement in which the several leaves are so supported that they will overlap but not become entangled with each other in use;

Fourth, to provide a record filing means of this class in which the accounting leaves and their supporting folder are interlocked and overlapped relatively to each other without added parts or portions;

Fifth, to provide a novelly constructed file folder for records of this class;

Sixth, to provide a novelly constructed folder in combination with visible index loose-leaf accounting means; and

Seventh, to provide a record filing means of this class which is very simple and economical of construction, easy to operate, efficient in its action and which will not readily deteriorate or get out of order.

With these and other objects in view as will appear hereinafter, our invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a perspective view of our record filing means showing varying positions of varying accounting loose-leaves and showing portions broken away to facilitate the illustration showing the file folder opened ready for use; Fig. 2 is a fragmentary view from the opposite side of the folder front shown from the inside; Fig. 3 is an enlarged sectional view taken from the line 3—3 of Fig. 1 and Fig. 4 is a fragmentary side elevational view of one of the single accounting leaves disassociated from the folder.

Similar characters of reference refer to similar parts and portions throughout the several views of the drawing.

The file folder 1, single accounting leaf 2, and double accounting leaves 3 constitute the principal parts and portions of our record filing means in its preferred form.

5 The folder 1 is preferably a rectangularly shaped envelope with a front portion 1a, a back portion 1b which is a folded continuation of the front portion 1a and a cover portion 1c which is a folded continuation of the portion 1b, all as shown best in Fig. 3 of the drawing. The portions 1b and 1c are similar to the conventional folder except the edge of the cover 1c is provided with a plurality of curved notches 1d which extend substantially the depth of the extended portion of the member 1b past the portions 1a and 1b. The space between these notches 1d is provided for the index characters for the folder. Those not used on this particular folder may be removed, as will be hereinafter described.

10 15 The front portion 1a is provided at each side substantially three quarters of an inch from the side edge with slots 1e and 1f. These slots extend from a slight distance from the end at point 1g and extend toward the other end and terminate quite a little distance from the opposite end as designated 1h so that the accounting leaves will not extend below the file folder 1. These slots are simply slits cut in the paper sheet forming the front member 1a and all the rest of the sheet 18 is preferably intact and complete. The member 1a is secured at its opposite ends to the member 1b by means of reinforcing strips 1j and 1k, as shown best in Fig. 1 of the drawing.

20 25 Supported by this front member 1a is a plurality of single and double accounting leaves 2 and 3, respectively. These accounting leaves 2 are made of paper, preferably thinner than the front member 1a of the folder 1, or other suitable material and are slightly narrower than the front member 1a, as shown best in Figs. 1 and 2 of the drawing. They are each provided with slits 2a and 2b at opposite sides substantially three quarters of an inch from the normally upper edge and leaving a loose ended tab member 2c which 30 35 is adapted to be offset when positioned on the front member 1a ready for use at dash line 2d, all shown best in Fig. 4 of the drawing.

40 45 Extending from the tab members 2c on opposite sides of the sheet 2 in alignment with the slits 2a and 2b are perforate lines 2e and 2f which form fold lines so that the leaves readily fold clear across the sheet at the lines 2e and 2f. These tab portions 2c are positioned through the slits 1e and 1f so that they extend on the 50 55 opposite side of the front member 1a from the

rest of the sheet and extend outwardly towards the edge as shown best in Fig. 2 of the drawing so that the edges of the members 2c rest against each other in the slits, as shown best in Fig. 2 and therefore do not overlap but interlock with each other against overlapping, the portion 2g extending from one side of the front member 1a to the opposite side. These portions 2g engaging with each other prevent any overlapping or nesting of the sheets. The portion 2h of the sheet may be provided with either single or double entry account lines for forms of various kinds as desired and extend some six or eight inches in width from the perforate line 2f, the form being printed on both sides of the sheet portion 2h so that either or both sides may be used in continuity in the accounting, the portion 2i being the same as the portion 2h except very narrow and both portions 2i and 2h are positioned above the member 1 while the portion 2c is below the same.

As shown in Fig. 1 of the drawing, sheets designated 3 are double sheets and may be utilized in interrelation with the single sheets or separately as desired. The sheets 3 are the same as the sheets 2 throughout except that the portion 2i of the sheet 2 is extended so that it is substantially one-half inch wider than the portion 2h so that it extends past the portion 2h when the parts are folded down together flat and both of these sheets may be used on both sides with suitable forms printed thereon for the purpose desired.

The operation of our record filing means is substantially as follows: The folder 1 is preferably of the proper length and width for use transversely in the conventional filing cabinet and is in envelope form provided with a cover flap portion 1c which is enough wider than the folder to form index portions 1 which are separated by the grooves 1d. At the base of the grooves 1d is provided a line 1m which may be utilized for shearing the portions of the tabs 1 not used in the particular folder where they are placed one behind the other so that they can be seen in their relative relation. Between the front 1a and the back 1b is a pocket which may be used for storage filing purposes for loose leaves 2 or 3, which may be removed after they are filled, thus providing storage for transfer of the particular accounting leaves. The front portion 1a with the side slits 1e and 1f forms the support for the accounting leaves 2 or 3 which are placed in position by placing the tabs 2c through the slits 1e and 1f at the opposite sides of the front member 1a and pressing the tabs 2c against the opposite side positioned against each other. If some accounts are considerably longer than others that would require the double sheets, the double sheet is used, or if the account is relatively short the single sheet is used. There may be three or four single sheets and then a double or the whole may be composed of single sheets or the whole may

be composed of double sheets, all to suit the particular account. These sheets may be readily replaced and substituted and may be shifted upwardly on the front member 1a or downwardly at their free edge for reading or writing thereon on either side of either or double sheet and when they are no longer needed they may be transferred into the pocket between the front and back members 1a and 1b.

10 Though we have shown and described a particular construction, combination and arrangement of parts and portions we do not wish to be limited to this particular construction, combination and arrangement but desire to include in 15 the scope of our invention the construction, combination and arrangement substantially as set forth in the appended claims.

Having thus described our invention, what we claim as new and desire to secure by Letters Patent is:

1. In a record filing means of the class described, an accounting sheet composed of relatively light flexible paper folded upon itself to provide two adjacent wall portions forming a pocket therebetween, one portion being provided with two spaced perforate lines in spaced relation from the opposite side edges of said sheet, the perforate lines terminating in slits in the opposite edges of said sheet leaving loose ended tabs at each side edge to form securing members for said sheet, and a filing folder in envelope or pocket form, the front side of which is provided with slits at its opposite side edges spaced from said edges, said slits adapted to receive the tabs 25 of said accounting sheet, which tabs extend into the pocket of said folder, said folder provided with a cover sheet arranged to extend past the margin of said folder when in closed position and provided with removable index sections in its extended margin.

2. In a record filing means of the class described, an accounting sheet composed of relatively light flexible paper folded upon itself to provide two adjacent wall portions forming a pocket therebetween, one portion being provided with two spaced perforate lines in spaced relation from the opposite side edges of said sheet, the perforate lines terminating in slits in the opposite side edges of said sheet leaving loose 45 ended tabs at each side edge to form securing members for said sheet and a filing folder in envelope or pocket form, the front side of which is provided with slits at its opposite side edges spaced from said edges, said slits adapted to receive the tabs of said accounting sheet, which tabs extend into the pocket of said folder, said folder provided with a cover sheet arranged to extend past the margin of said folder when in closed position.
